UNITED STATES PATENT OFFICE.

ANTON R. NELSON, OF JANESEVILLE, CALIFORNIA.

AUTOMATIC BATTERY CUT-OUT FOR TELEPHONE-CIRCUITS.

1,072,490.

Specification of Letters Patent.

Patented Sept. 2, 1913.

Application filed May 8, 1913. Serial No. 766,282.

To all whom it may concern:

Be it known that I, ANTON R. NELSON, a citizen of the United States, residing at Janesville, in the county of Lassen and State of California, have invented certain new and useful Improvements in Automatic Battery Cut-Outs for Telephone-Circuits, of which the following is a specification, reference being had therein to the accompanying drawing.

My invention relates to telephone systems and especially to those having a plurality of subscribers on the same line.

The object of the invention is to permit the receiver at a station to be connected across the line without closing the local battery circuit, whereby the subscriber may listen in to ascertain when the line becomes free, without wasting current or running down his battery. In order to attain this object, I provide an interlocking contact device, one element of which is mounted on the switch hook and the other on the ringing generator, in such manner that when the receiver is removed from the hook, the receiver circuit is closed without the battery or transmitter, and in order to close the latter, the generator must be operated.

My invention is illustrated in the accompanying drawing in which the figure is a diagram of one of several stations on a party line, equipped with my invention.

Referring to the drawing, t' and t^2 are the line terminals of the station instrument and t^3 is the ground terminal.

Q is the ringer, G is the generator, H is the switch hook, T the transmitter, R the receiver, B the battery, C the condenser, P a push button for ringing, and I the induction coil with primary and secondary windings i and i^2 respectively. The switch hook is pivoted at h and carries a special stop lever h' pivoted at h^2 and hanging freely over the disk g on the crank shaft g' of the generator G . This crank shaft is provided with the usual cam, indicated at g^3 , by which the insulating button g^4 at the end of the crank shaft outside of the disk g acts to throw over the spring s and shift the line connection from talking to ringing when the crank of the generator is turned, as usual.

The circuits of this equipment will appear in detail from the statement of operation, but it may be stated that the only normal connection is through the ringer Q which is bridged across the line. When the sub-

scriber calls, he removes the receiver and turns the crank of his generator, which enables him afterward both to talk and to hear; but when he wishes to listen only, he removes the receiver without touching the generator. The member h' then rests upon the disk g and closes the listening circuit through receiver R as will appear hereafter.

The circuits are as follows: The ringer circuit is t' , 1, 2, 3, 4, t^2 . The ringing or generator circuit while the crank is being turned is: t' , 1, 5, 6, H , 8, 9, G , g^4 , s^2 , p , p' , s^2 , s , 10, 4, t^2 . The battery transmitter circuit is: B , 11, T , 12, 7, 6, H , 8, 13, i , 14, battery. This is closed only when the hook is all the way up with the receiver off and the lever h' clear of the disk g . The listening circuit with hook only partly operated is: t' , 1, 5, 6, H , 8, 13, i' , R , C , s' , s , 10, 4, t^2 . This circuit may also be traced from 5, 6, H , h' , g , G , 9, 13, i' , etc. The contact 6 touches the tail of the switch hook, but does not close upon contact 7 until stop lever h' is clear of the disk g .

The operation is as follows: Normally only the ringer circuit through Q is closed. In making a call for another party, the user removes the receiver R from the hook H which thereupon tilts until stop lever h' rests on the disk g , whereupon the crank of the generator is turned to ring, and at the first movement the cam g^2 throws the shaft g' endwise, clears the disk g from the stop lever h' so that the switch hook will tilt farther, and complete the closure of springs 6 and 7; and finally the shaft breaks apart springs s , s' and closes s , s^2 , thereby completing the ringing circuit. When the crank is released, the shaft is drawn back by the cam but the stop lever h' remains closed. Conversation can then proceed as usual.

In receiving a call, the subscriber hearing the ringer Q sound takes down his receiver and turns the crank of his generator for a brief answer-back ring, which also trips the stop lever h' and closes his talking circuit. For listening in without talking, the subscriber simply takes down the receiver, and thereby closes the first listening circuit t' , 1, 5, 6, H , 8, 13, i' , R , C , 10, 4 and t^2 . All other circuits remain unaffected.

Having thus described my invention what I claim and desire to secure by Letters Patent is:

1. In a telephone station apparatus, a

transmitter, a receiver, a switch hook and a calling device, with circuit connections for each, contacts in the transmitter and in the receiver circuits controlled by the switch hook, means normally permitting the switch hook to close the receiver circuit but blocking closure of the transmitter circuit, and means becoming active in the operation of the calling device to remove said block and 10 permit the closure of the transmitter circuit, substantially as described.

2. In a telephone substation apparatus, a transmitter in a local circuit, a receiver, ringing generator, and switch hook, contacts adapted to be successively closed by the switch hook in its movement and included in the receiver circuit and in the transmitter circuit respectively, a stop element carried by the switch hook, and a co-operating element under control of the ringing generator in its operation, adapted to normally permit closure by the switch hook of contacts in the receiver circuit only, but when the generator has been operated, 20 adapted to be removed from the path of the blocking element of the switch hook to complete actuation thereof in the closure of the transmitter circuit, substantially as described.

3. In a telephone substation apparatus, a switch hook H, generator G, transmitter T, battery B, and receiver R, said switch hook provided with contacts 6 and 7 closed successively in its movement, the contact 6 adapted when closed to complete the circuit 35 of the receiver R through the switch hook, and the contact 7 when closed adapted to complete the circuit of the transmitter T through the battery B and the switch hook, said hook being further provided with a stop lever h' and the generator G provided with a co-operating stop g normally lying in the path of said stop lever and so related thereto as to permit the closure of contact 6 only, but adapted when the generator is 40 operated to be moved out of the path of said lever h' and thereby to permit the further movement of the switch hook and the closure of the transmitter contact 7, all as and for the purpose intended, substantially 45 50 as described.

In testimony whereof I affix my signature in presence of two witnesses.

ANTON R. NELSON.
